DEVICE FOR TESTING THE ABRASION-RESISTANCE OF SURFACES OF METALLIC ARTICLES William J. Campbell, 38 Mair St., Glasgow, S.W. 1,
Scotland

Filed July 26, 1957, Ser. No. 674,375

2 Claims. (Cl. 73—7)

The subject of this invention is a device for testing the abrasion or wear resistance of surfaces of metallic articles, more particularly hard anodic surfaces of articles of aluminium or of aluminium alloy.

The primary object of the present invention is to provide means for ascertaining readily the abrasion- or wear-resistant properties of hard anodic coatings on aluminium or aluminium alloy articles of different shapes and dimensions.

A further object is to provide means for ascertaining the abrasion- or wear-resistant properties of any anodic coatings on aluminium or aluminium alloy articles or of metallic coatings or surfaces on articles not necessarily made of aluminium or of aluminium alloy.

The method according to the invention consists in scratching or scoring the surface to be tested with a stylus subjected to a predetermined load in such wise as to form on the said surface superposed series of substantially equi-spaced zig-zag scratches of which adjacent scratches are spaced apart a distance of, say, 0.005 inch, the amount of material removed from said surface being a measure of the abrasion- or wear-resistance of said surface.

Each of the series of scratches may consist of 20 or 30 scratches which made each be about 0.05 inch to 0.125 inch in length.

In the testing of a hard-anodised surface on an aluminium article, an approximate measurement may speedily be obtained from the visual appearance of the surface after the formation of several, say 10, superposed series of scratches, the load on the stylus having been adjusted in such wise that a visible amount of debris from the abraded surface is deposited on the stylus. The abrasion resistance of two hard-anodised surfaces may then be compared as being in direct proportion to the number of superposed series of scratches necessary to produce the same amount of debris. A more precise measurement may be obtained if the actual depth of the scratches is measured after the formation of a selected number of superposed series of scratches. The abrasion resistance is then assessed in inverse proportion to the depth of the scratch, i.e., the softer is the surface, the deeper will be the scratch and vice versa.

A device for performing the method according to the invention is illustrated in the accompanying drawings in which:

Fig. 1 is a side elevation of the device.

Fig. 2 is a section on the line 2—2 of Fig. 1.

Referring to the drawings, 1 denotes the base of the device which is bored at 3 for mounting of the base 1 on an upright externally screw-threaded pillar (not illustrated) to provide for varying the height of the device from an article to be tested.

4 denotes an upright arm pivotally mounted on a fulcrum 5 for oscillatory movement through an arc of a few degrees. The arm 4 is normally urged in the direction towards a cam 6 by a tension spring 7 anchored at one end to the arm 4 and at the other end to a pin 8 up-

2

standing from the base 1. The periphery of the cam 6 presents a plurality of equi-spaced teeth 6¹.

A cam follower 6² in the form of a roller the axis of which is parallel to that of the fulcrum 5 is mounted on the arm 4 to engage the periphery of the cam 6.

5 A substantially horizontal reciprocating bar 9 pivoted intermediate its ends on a fulcrum 10 mounted in the arm 4 carries at one end a stylus 11. The other end portion of the bar 9 is pointed and is located adjacent to a microscope (illustrated diagrammatically at 12) adapted to measure the extent of vertical movement of the bar 9.

10 A cam follower 13 in the form of a roller the axis of which is substantially parallel to the bar 9 is mounted on the arm 4 and is engaged with a cam 14 co-axial and integral with the cam 6. The arm 4 is slidably mounted on its fulcrum 5 and is normally urged by a compression spring 15 in the direction to engage the cam follower 13 with the cam 14. Both cams 6, 14 are integral with a wheel 16 mounted on a spindle 17.

15 20 In practice, when the spindle 17 is rotated at, say, 5 r.p.m., the wheel 16 and the associated cams 6, 14 also rotate; the follower 6² tracks the periphery of the cam 6 to effect oscillation of the arm 4 and reciprocation of the bar 9; and the follower 13 engaging the cam 14 causes reciprocation of the arm 4 transversely of the axis of reciprocation of the bar 9.

25 To test the abrasion- or wear-resistance of, for example, a hard-anodised surface, the device is positioned with the stylus 11 resting on the surface; a load such as a weight 9', on the arm 9 is adjusted so as to apply the desired load to the stylus 11; the positions of, for example, a marked tooth 6¹ of the cam 6, and of the point of the free end portion of the bar 9 are noted; and the spindle 17 is rotated at constant speed for, say, 10 revolutions, until the cam assumes its identical original position.

30 35 During reciprocation of the bar 9 and of the arm 4, the stylus 11 scores the surface to be tested with zig-zag scratches and the pointed end portion of the bar 9 rises substantially vertically. After rotation of the spindle 17 has been stopped, the distance through which the point of the bar 9 has moved is measured by means of the microscope 12, the measurement being a measure of the wear on the surface caused by the stylus 11.

40 45 The cam 14 is symmetrically formed as a cylinder intersected by a plane inclined to the axis of the cylinder. The cam 14 is co-axial with and secured to the cam 6 in such wise that both cams rotate simultaneously at the same angular velocity. The radial position of the cam 14 relative to the curved surface of one of the equi-spaced symmetrical teeth 6¹ determines the coincidence or otherwise of the superposed scratches produced by the stylus 11.

50 55 When the radius line of maximum axial projection of the cam 14 is angularly coincident with a radius on the cam 6 of the crest or the root of one of the teeth 6¹, the two cams 6, 14 may be said to be in a state of symmetry and the scratches of a pattern produced by the stylus 11 will be precisely coincident with the scratches of a preceding pattern on which said first-mentioned pattern is superposed because the reversal traversing action of the cam 14 at its maximum or its minimum limit on its follower 13 will cause the follower 6² of the cam 6 to retrace precisely its previous path whereas, when the radius line of maximum radial projection of the cam 14 is angularly coincident with a radius of the cam 6 which is equal in length to half of the radius of the cam 6 to the crest plus half of the radius of the cam 6 to the root, the relative positions of the two cams 6, 14 are at their maximum state of asymmetry, so that the reversal action of the cam 14 on its follower 13 will cause the follower 6² of the cam 6 to continue its previous path for $\frac{1}{4}$ cycle, whereby a pattern of scratches produced by the stylus 11 will be wholly out of phase with a preceding pattern on which said first-

mentioned pattern is superposed, with the result that the superposed scratches will cross the underlying scratches in the centre of their zig-zag course.

In operation of the device the symmetrical condition is preferable for precise measurement of wear while the asymmetrical condition is preferable for visual assessment of the wear as there is then more break-up of the surface material where the scratches cross one another.

The cams 6, 14 may be so arranged that the relative rates of reciprocation of the bar 9 and of the arm 4 are approximately 40:1. Thus, if the cam 6 reciprocates the bar 9 at 200 strokes per minute, the cam 16 will reciprocate the arm 4 at 5 strokes per minute.

The amplitude of reciprocation of the arm 4 is related to the dimensions of the point of the stylus 11 which may be constituted by a diamond or a sapphire pyramid or by a metallic needle or a pointed abrasive member.

During reciprocation of the bar 9, the stylus 11 will score a V-shaped groove in the surface being tested. To avoid undue protraction of the time taken for the test, the load on the stylus 11 is adjusted so that the rims of adjacent grooves are close to one another after only a few reciprocations of the bar 9.

As the depth of the surface removed by wear during the test is usually of the order of 0.0001 inch and the area tested is of the order of 0.01 square inch, the test does not render the surface unserviceable and can readily be used in connection with a relatively small article, such as a spindle having a diameter of $\frac{3}{16}$ of an inch, or with a tube the internal diameter of which is of the order of $\frac{3}{8}$ of an inch. The embodiment illustrated in the drawing is that which has proved suitable for the testing of the general range of sizes and shapes of articles met with in practice. When very large surfaces are to be tested, the device is inverted on the screwed pillar which accommodates the base 1. By this means it is then possible to lower the stylus 11 down to the level of the base 1 and to use it for testing the surface with appropriate adjustments such as inverting the stylus from the direction illustrated, increasing the length of the vertical arm 4 beyond the length illustrated and reversing the direction of the load on the stylus.

In order to establish a relationship between the measurement of surface hardness effected by the device ac-

cording to the invention and conventional devices for measuring surface hardness, a diamond pyramidal stylus is traversed a few times under a predetermined load over a steel surface of known Brinell or Rockwell hardness and the depth of the score produced on the steel is measured. The same stylus under the same load is then traversed the same number of times over a hard-anodised surface to be tested and the depth of the score produced is again measured. The measurement of the hardness of the anodic coating is then related to the Brinell or Rockwell hardness number obtained in connection with the test on the steel.

While the device has been primarily adapted to measure the abrasion resistance of hard-anodic coatings, it may also be used for measuring the hardness of ordinary anodic coatings or indeed of thin surface layers on articles not necessarily consisting of aluminium or aluminium alloy by adjusting the load on the stylus to one which will cause the stylus to produce scores of a depth considerably less than the thickness of the surface layer.

What is claimed is:

1. A device for testing the abrasion-resistance of coatings produced electro-chemically on metallic articles, including a bar, a stylus connected to one end of said bar, and means connected to said bar intermediate its ends for effecting relatively rapid reciprocation of said bar in one direction in a substantially horizontal plane and relatively slow reciprocations in the same plane in a direction transversely of the axis of reciprocation in said first direction, said bar and associated stylus being free to oscillate in a vertical plane.
2. A device as claimed in claim 1, in which the bar is pivoted intermediate its ends to a substantially upright arm pivotally mounted on a fulcrum, and cam means is operable to oscillate said bar about the axis of said fulcrum and to reciprocate on said fulcrum.
